US LLP(57) **CLAIM**

The ornamental design for tire balancing weight, as shown and described.

DESCRIPTION

FIG. 1 is a perspective view of a first embodiment of my design for a balancing weight for tires;

FIG. 2 is a top view of the first embodiment;

FIG. 3 is a bottom view of the first embodiment;

FIG. 4 is a left side view of the first embodiment;

FIG. 5 is a right side view of the first embodiment;

FIG. 6 is a front view of the first embodiment; and,

FIG. 7 is a rear view of the first embodiment.

All other surface(s) or portion(s) of the tire balancing weight not shown in the figures or otherwise described in the specification form no part of the claimed design.
